F. W. FULLERTON.
NEWSPAPER CONVEYER.
APPLICATION FILED MAY 20, 1911.

1,138,609.

Patented May 4, 1915.

UNITED STATES PATENT OFFICE.

FREDERICK W. FULLERTON, OF ST. PAUL, MINNESOTA, ASSIGNOR TO DISPATCH CONVEYOR COMPANY, A CORPORATION OF MINNESOTA.

NEWSPAPER-CONVEYER.

1,138,609.

Specification of Letters Patent.

Patented May 4, 1915.

Application filed May 20, 1911. Serial No. 628,598.

To all whom it may concern:

Be it known that I, FREDERICK W. FULLERTON, a citizen of the United States, residing at St. Paul, in the county of Ramsey 5 and State of Minnesota, have invented a new and useful Improvement in Newspaper-Conveyers, of which the following is a specification.

My invention relates to improvements in 10 newspaper conveyers and more particularly to a conveyer, which is adapted for use in connection with the modern printing press.

An object of my invention is to provide a 15 conveyer for newspapers and other printed papers, which will receive the papers from the press and transmit them by any convenient route to a delivery table where the papers are usually stacked and counted.

My conveyer is particularly adapted to 20 the transmission of folded papers without smearing the fresh printer's ink through contact with the belts and without creasing or breaking the folded papers where the conveyer changes direction. It also reduces 25 wear between the papers and belts and is practically noiseless. My improvement also causes a pair of said belts to tightly and evenly grip and accommodate printed papers 30 of different sizes and weights with substantially uniform pressure whereby the papers are prevented from creeping and becoming 35 disarranged or damaged. The construction also admits of quickly repairing broken or damaged parts with ease in case of accident.

The mechanism with which the conveyer is 40 operated is also simple in construction and light in operation being applied in use around sharp corners and through ceilings and walls with little difficulty.

In the accompanying drawing forming 45 part of this specification, Figure 1 is a diagrammatic view, showing the application of my invention to several of the different conditions of a newspaper conveying system; Fig. 2 is an end view of a detail of the 50 conveyer system; Fig. 3 is a plan of a detail of the conveyer system; Fig. 4 is a plan of a portion of one of the belts, and Fig. 5 is a side view of one of the sets of pulleys or sheaves.

In Fig. 1 of the above drawing is illustrated my improved conveyer having a newspaper receiver A, a downward to horizontal change in direction B, a horizontal to a

downward change of direction C, and a 55 counting and stacking table D.

The conveyer is adapted to be connected to a printing press not illustrated to operate by any convenient source of power in synchronism with the delivery mechanism of 60 the press. As the papers E pass through the conveyer, which may be of any length desired and fitted with any of the changes of direction shown, to bring the papers to the required delivery point, they are passed on 65 to the table D and stacked and can be removed from the table as desired.

A primary feature of my invention consists in arranging carrier belts composed of substantially endless helical spring wire 70 strands 44, (see Fig. 4), held under tension so that the adjacent sides or surfaces of co-operating belts are adapted to grip papers between said sides and convey them evenly 75 from one point to another without the papers becoming disarranged or slipping and the freshly printed surfaces smudged. An embodiment of this idea and other features of novel construction are incorporated in the apparatus set forth in the following description. 80

The receiver A consists of a plurality of belts 2 running over sheaves 3 and 4, the sheaves 3 being mounted at substantially equal distances apart upon a shaft 5 and the 85 sheaves 4 mounted in the same manner on the shaft 6, all of said sheaves being of equal diameter, whereby all of the belts 2 are adapted to lie with their upper and lower sides respectively in approximately 90 adjacent horizontal planes. The shafts 5 and 6 are journaled upon suitable supports such as 7, which are mounted upon the floor or ceiling 8 of the building of a structure containing the conveyer system, the shaft 6 95 being arranged above an opening 9 in said floor or ceiling, so that the downward extension of the conveyer may pass freely through said opening. The downward extension F of the conveyer is composed of 100 a group of belts similar to belts 2 passing over sheaves 10, (see Fig. 5), on the shaft 6 lying adjacent to the sheaves 4, and over sheaves 11 on a shaft 12, which is supported below the ceiling 8. The sheaves 4 and 10 105 are of the same diameter and the belts 13 travel at the same surface speed as the belts 2 serving to assist in conveying the papers

from a horizontal direction downwardly on to another group of horizontal belts 14. The shaft 12 is of similar construction to the shaft 6, being provided with sheaves similar 5 to 4 and 10 for the downwardly extending belts 13 and the horizontal belts 14, the latter also passing around sheaves 15 on a shaft 16 at the turn C, the belts 14 passing through an opening 17 in the upper portion 10 of a partition such as 18. After passing through said opening and around the sheaves on the shaft 16, the papers are assisted in being carried downwardly by downwardly extending belts 19 passing over 15 one of the sets of sheaves on the shaft 16, which is similar to the construction illustrated in Fig. 5, and over another set of sheaves 20, carried by the shaft 21. The papers upon reaching the lower end of the 20 belt 19 are turned by a laterally extending set of belts 22 passing around sheaves 23 on a shaft 24, and sheaves on the shaft 21 which are similar to those illustrated in Fig. 5, whereupon the papers are delivered 25 upon the table D, which is in the form of a frame having transverse shafts 25 journaled in its ends and carrying sets of sheaves 26 and 27, around which a set of belts 28 are passed. The papers are deposited upon 30 the belts 28 and stacked in the usual manner by moving the belts with their upper sides away from the delivery end of the conveyer.

Arranged above the receiving belts 2 is an auxiliary set of belts 30, traveling over sheaves 31 on the shaft 32 and over sheaves 33 on the shaft 34, the lower sides of said belts being adapted to coöperate with the upper sides of the belts 2 to assist in conveying the papers in a forward direction. Situated adjacent the sides of the belts 13, which convey the papers is another auxiliary set of belts 35 having sides which also coöperate with the adjacent sides of the 40 belts 13 to assist in conveying the papers forwardly in a downward direction upon the upper sides of the belts 14. The belts 35 pass around sheaves 36 on a shaft 37, and a set of sheaves similar to the sheaves 45 50 10, mounted upon the shaft 34, said shaft 34 and the sheaves which it carries being similar in construction to that illustrated in Fig. 5. At the point where the papers turn from the receiving belts 2 into a downward direction 55 and from the belts 13 into a horizontal direction, guides 40 are positioned in the form of guide arms, which are mounted upon shafts such as 41 and urged against the papers by springs 42, thus assisting the 60 papers in turning evenly without becoming disarranged or damaged. Guides 43 are similarly placed at the turn from a horizontal direction, in which the belts 14 travel, into a downward direction assumed by the 65 belts 19.

All of the belts employed in the conveyer are made of helical spring wire 44, whereby the sides or surfaces of the belts are held under tension to prevent slipping upon the pulleys and causing the adjacent sides of 70 the belts, which coöperate to hold the papers between them and carry the papers forwardly in a positive manner without creasing and becoming disarranged or the fresh printer's ink smudged. 75

All of the sheaves are driven by link belts and sprockets 45 and 46 connected with their shafts so that the helical belts are positively driven wherever they pass over the sheaves, whereby the belts are relieved from all driving strain and sagging and are caused to more evenly grip the papers without permitting the papers to collect in bunches. The auxiliary belts are driven by trains of gears 47 and 48 connected with shafts 6 and 34 and 16 and 49, which serve to transmit power from the main helical belt driving elements to the auxiliary helical belts which are used for the purpose of coöoperating with said main belts to grip the papers and carry them evenly around each turn and upon each up and down stretch. 85 90

When desired idle sheaves such as 50 may be arranged below up and down stretches of the helical main and auxiliary belts to offset the line of travel and cause the belts to more positively grip the papers and carry them evenly. A short run does not require the use of these offsetting sheaves but where the stretches are long and up and down and the helical belts small in diameter and comparatively weak, said sheaves are desirable. 95 100

The auxiliary belts 30 run from a high point to a low point of travel as compared with the horizontal runs for the purposes of gradually guiding the papers into the bite of the belts and coöoperating with the guides 40 to turn the papers around a corner. 105 110

The delivery table D has motion transmitted to its carrier belts 28 by an eccentric 51 on the shaft 21 and a pawl 52 carried by said eccentric and coöoperating with the teeth of a ratchet wheel 53 secured upon the shaft 25 nearest the delivery end of the belt 22. In this manner a step by step motion at a relatively slower advancing speed than that of the main carrier belts is imparted to the receiving belt, causing the papers to be stacked in convenient position to be counted and handled by the operators. The various revoluble elements and guides are suitably journaled or supported by brackets such as 7 and 54, or by the walls, ceilings and floors of a building, or by any other suitable supports. 115 120 125 130

The conveyer admits of application to the various structures and conditions surrounding printing presses and while the appa-

ratus shown illustrates one mode of application wherein the papers are carried from a high to a low point, it is obvious that the invention is applicable with equal efficiency 5 where the transmission is from a low to a high point.

In accordance with the patent statutes I have described the principles of operation of my invention together with the apparatus which I now consider to represent the best embodiment thereof but I desire to have it understood that the construction shown is only illustrative and that the invention can be carried out by other means and applied 15 to uses other than those above set forth within the scope of the following claims.

Having described my invention, what I claim as new and desire to protect by Letters Patent is:—

20 1. In a conveyer of the class set forth, a pair of substantially parallel helical spring wire belts having adjacent sides held under tension close together and means for driving said belts with their adjacent sides in the same direction and at substantially the same speed to advance papers placed between them.

25 2. In a conveyer of the class set forth, a plurality of pairs of substantially parallel helical spring wire belts, each of said pairs having adjacent sides held under tension close together and means for driving said belts with their adjacent sides in substantially the same direction and at substantially the same speed to advance papers placed between them.

30 3. In a conveyer of the class set forth, a pair of substantially parallel helical spring wire belts having sides held under tension and adjacent, means for driving said belts with their adjacent sides in the same direction and at the same speed to advance papers placed between them, and means for guiding papers between said adjacent sides.

35 4. In a conveyer of the class set forth, a pair of substantially parallel helical spring wire belts having sides held under tension

and adjacent, means for driving said belts with their adjacent sides in the same direction and at substantially the same speed to 50 advance papers placed between them, and means for delivering papers from between said adjacent sides.

5. A conveyer of the class set forth, comprising, in combination, a pair of carrier 55 belts having adjacent sides coöperating together and traveling in the same forward direction, a third belt having one side traveling in a forward direction and arranged with said side in position to receive papers 60 from between the adjacent sides of said pair of belts, and a guiding element arranged to assist in delivering the papers from between said adjacent sides on to the said side of said third belt, all of said belts being composed of coils of wire acting under spring tension.

6. In a conveyer of the class set forth, a belt composed of helical resilient wire, sheaves over which said belt travels, and 70 means for directly driving each of said sheaves, whereby driving tension is relieved from said belt.

7. In a conveyer of the class set forth, a belt composed of suitable coiled wire, 75 sheaves over which said belt travels and means for directly driving each of said sheaves, whereby driving tension is relieved from said belt.

8. In a conveyer of the class set forth, a 80 belt composed of a series of angularly disposed sections, each of said sections comprising a plurality of endless suitably coiled wires, sheaves over which said sections travel, and means for driving said sheaves 85 whereby driving tension is relieved from said belt sections.

In testimony whereof, I have signed my name to this specification, in the presence of two subscribing witnesses.

FREDERICK W. FULLERTON.
